UNITED STATES PATENT OFFICE.

FRANZ METTLER, SOHN, OF ARTH, SWITZERLAND.

DEVICE FOR SINGEING THREADS OF ANY KIND.

Application filed December 28, 1923. Serial No. 683,210.

To all whom it may concern:

Be it known that I, FRANZ METTLER, Sohn, a citizen of the Republic of Switzerland, residing at Arth (Ct. Schwyz), Switzerland, have invented certain new and useful Improvements in Devices for Singeing Threads of Any Kind, of which the following is a specification, reference being had therein to the accompanying drawing.

10 The subject matter of the present invention is a device for singeing by means of a gas threads of any kind and which is characterized by the feature that for the purpose of obtaining an intense singeing action a tubular burner for the gas is provided through which the thread has to pass.

15 A constructional example of the singeing device according to the present invention is illustrated on the accompanying drawings, in which:

Fig. 1 is a vertical section through the device,

Fig. 2 is a vertical section along line II—II in Fig. 3,

20 Fig. 3 is a horizontal section along line III—III in Fig. 1, and

Fig. 4 shows a general arrangement in elevation.

25 In the drawings 1 denotes an upright cylindrical tube arranged inside a surrounding tube 2 and supported by the latter. Between the surrounding tube 2 and the inner tube 1 an annular space 3 which is closed at top and bottom is provided, to which a branch pipe 4 for supplying a combustible gas is connected, the latter being distributed over the space 3. The tube 1 is provided with several rows of radially disposed apertures 5 through which the gas passes. The burner 30 formed in this manner is provided with a longitudinal slot 6 permitting the thread A to be introduced into the interior of the burner tube 1. The thread to be singed passes over guide rollers 7 so arranged that the thread is situated in the centre of the tube and on being moved through the tube has to pass through the singeing flame formed by each row of apertures 5 which flame acts on and influences the outside of the thread. 35

40 In this manner a one-side singeing action is prevented. Through the open ends of the tube 1 and through the slot 6 a quantity of air reaches the interior of the tube 1 that is sufficient for sustaining a complete combustion of the gas.

The burner is fitted to a pipe 8 the lower

end of which is connected to a conduit 14 leading to an exhaust fan 15. Near the lower and the upper end of the burner the pipe 8 is provided with suction openings 9 and 10 respectively through which the combustion gases and the charred fibres are removed. The burner is further protected by a cover 11 mounted in hinges 12 on the pipe 8 forming a chamber 13 around the burner, which chamber is in open communication with the suction aperture 10 of the pipe 8. This chamber is provided for the purpose of attaining an efficient removal of the residues of the singeing process even in case rough threads having long fibres are treated.

45 A plurality of the described burners may be arranged on one frame as is illustrated in Fig. 4. Two pipes 8 enclosing the burners proper are connected to an exhaust conduit 14 leading to a fan 15 and to branch tubes 4 of a conduit 16 for supplying a combustible gas. The thread A to be treated, which is unwound from a bobbin 17, arranged below each burner, passes over the lower guide roller 7, through the tube 1 and over the upper guide roller 7 to a winding device 18 by which the singed thread is wound upon reels 19.

50 I claim:

1. In a device for singeing threads of any kind, a tubular gas burner comprising a flame chamber in the interior thereof and through which the thread is to be drawn.

55 2. A device for singeing threads of any kind, comprising a tubular gas burner through which the thread to be treated has to pass and having an inner tube provided with a plurality of apertures for the gas to pass through and an outer tube surrounding said inner tube, a distribution chamber for the gas being formed by the annular space between said inner and said outer tube.

60 3. A device for singeing threads of any kind, comprising a tubular gas burner through which the thread to be treated has to pass and having an inner tube provided with a plurality of radially disposed apertures for the gas to pass through and an outer tube surrounding said inner tube, a distribution chamber for the gas being formed by the annular space between said inner and said outer tube.

65 4. A device for singeing threads of any kind, comprising a tubular gas burner through which the thread to be treated has to pass and having an inner tube provided

with a plurality of radially disposed apertures arranged in several rows for the gas to pass through and an outer tube surrounding said inner tube, a distribution chamber for the gas being formed by the annular space between said inner and said outer tube.

5. A device for singeing threads of any kind comprising a tubular gas burner having a flame chamber through the interior of which the thread to be treated has to pass, said burner having a longitudinal slot for introducing the thread into the flame chamber.

6. A device for singeing threads of any kind comprising a tubular gas burner having a flame chamber through the interior of which the thread to be treated has to pass, said burner having a longitudinal slot for introducing the thread into the flame chamber, a movable cover arranged outside said tubular burner, and a conduit adjacent to the lower end of said chamber for removing the residues of combustion by suction action from said burner, the residues being deviated by said cover from the burner into the conduit.

7. A device for singeing threads of any kind, comprising a tubular gas burner having an internal flame chamber substantially concentric with said burner through which the thread to be treated has to pass, a conduit for removing the residues of combus-

tion by suction action from said burner and supporting the latter, apertures being provided in said conduit to the rear of and below the burner for the deviation of the residues thereinto.

8. A device for singeing threads of any kind, comprising a tubular gas burner through which the thread to be treated has to pass, and having an inner tube provided with a plurality of radially disposed apertures arranged in several rows for the gas to pass through, an outer tube surrounding said inner tube, a distribution chamber for the gas being formed by the annular space between said inner and said outer tube, a conduit for removing the residues of combustion by suction action from said burner and supporting the latter, apertures being provided in said conduit above and below the burner for the passage of the residues, and a movable cover arranged outside said tubular burner, the residues being deviated by said cover from the burner into said apertures of said conduit.

9. In a device for singeing threads of any kind, a substantially vertical tubular gas burner comprising a flame chamber and means to draw the thread through the interior and longitudinally of the chamber.

In testimony whereof I affix my signature.

FRANZ METTLER, SOHN.
